(57) **CLAIM**

The ornamental design for a frame for making edible ice, as shown and described.

DESCRIPTION

FIG. 1 is a top, front, left perspective view of a frame for making edible ice showing the claimed design;

FIG. 2 is a top view thereof;

FIG. 3 is a bottom view thereof;

FIG. 4 is a top, rear, right perspective view thereof;

FIG. 5 is a bottom, front, left perspective view thereof; and, FIG. 6 is another perspective view thereof shown in an open position.

The broken lines in FIG. 6 are for illustrative purposes only and form no part of the claimed design.
